UNITED STATES PATENT OFFICE.

JACQUES BOHLI, OF SOLOTHURN, SWITZERLAND, ASSIGNOR TO THE FIRM SCINTILLA,
OF SOLOTHURN, SWITZERLAND.COMBINED LOCKING APPARATUS FOR THE DISTRIBUTING SWITCHES OF ELECTRIC-
LIGHTING INSTALLATIONS OF MOTOR CARS.

Application filed July 12, 1922. Serial No. 574,518.

To all whom it may concern:

Be it known that I, JACQUES BOHLI, a citizen of the Swiss Republic, and residing at No. 304 Obach, Solothurn, Switzerland, have invented certain new and useful Improvements in Combined Locking Apparatus for the Distributing Switches of Electric-Lighting Installations of Motor Cars, of which the following is a specification.

10 This invention has for its object to provide an improved combined locking apparatus for the distributing switch of electric lighting installations such as are employed in motor-cars.

15 As a rule such distributing switches comprise two main actuating members, namely a first member for distributing the current to the various consuming devices, and a second member for actuating the starter. Each 20 of these said members has its own locking apparatus which is separate from the locking apparatus for the other member. Frequently one of these locking apparatus is also utilised to effect the cutting out of the 25 ignition. This use of the locking apparatus is attended by the drawback that its position for cutting out can only be the one terminal position in which the locking is effected. In this manner it is not possible, 30 for instance during a night journey, to lock a lighting apparatus in a determined position, because this would necessitate also cutting out the ignition apparatus and stopping the car engine at the same time.

35 It has been proposed (see Swiss Patent No. G. 13826 to the firm Scintilla) to construct a combined locking apparatus in which the locking member may be moved into three positions: when it is in one terminal position the lighting control switch and the switch for cutting out the ignition apparatus are both locked; in its other terminal position it operates the starter and releases both the above-mentioned switches,

40 and in its mid position it releases the lighting control switch and the ignition cut-out switch so as to leave them free for operation, while at the same time it cuts out the starter.

45 The present invention resides in improvements in the foregoing three-position type of combined locking apparatus, wherein a locking pawl is employed mounted so as to be capable of rocking and biased so as to

tend to take up a locking position for the 55 purpose of holding the cut-out switch of the ignition apparatus in a position which prevents ignition, that is a non-operative position, when the locking member of the light-distributing switch is situated in its mid- 60 position. This locking pawl is arranged to be forced aside when the cut-out switch is moved in either direction by applied pressure.

When the locking member of the light 65 distributing switch is moved into its third or terminal starting position the pawl will be moved by the said locking member and will no longer restrain the cut-out switch of the ignition apparatus. This cut-out 70 switch is thereby unlocked and is then automatically moved by the action of its spring from its non-operative position into its operative position.

In the accompanying drawings which 75 illustrate diagrammatically the essential parts of a combined locking apparatus with a light-distributing switch and a locking pawl for the cut-out switch of the ignition apparatus:

Figure 1 shows the apparatus held by the operating key in the locked position with the cut-out switch of the ignition apparatus locked in the non-operative position;

Figure 2 shows the apparatus held by the 85 operating key in the unlocked position with the cut-out switch of the ignition apparatus locked in its non-operative position;

Figure 3 shows the apparatus held by the operating key in the starting position, in 90 which the cut-out switch of the ignition apparatus has been completely released and the starting motor circuit completed.

In the drawings the ignition cut-out switch *c* which can rock on the pivot *w* 95 can be opened and closed as desired by hand so long as the locking member *a* is not situated in the locking terminal position, shown in Figure 1. When it is moved into its non-operative position it is locked by the 100 locking pawl *s* which is pivoted at *v* and is held in its locking position against the stop *y* by a spring *t*. The switch *c*, the lighting control switch *b* and the locking member *a* are all hand operated, the latter 105 by the key *g*.

On applying increased pressure in the direction of the tension of its spring *q* the

cut-out switch *c* can be moved out of its non-operative position into the operative position shown in Figure 3, and vice versa. By applying pressure in the opposite direction 5 the said switch *c* can be moved out of the operative position into the non-operative position. In each case the pawl *s* is forced aside in opposition to the action of its spring *t*.

10 On the upper end of the locking member a there is located a pin u which engages the end of the locking pawl s . If now, by means of the key g , which is capable of locking the system in any of the three 15 positions illustrated, the locking member a be brought into the terminal position shown in Figure 3, in which the switch magnet o receives current through the contacts d and f and closes the switch p and thereby brings 20 the starting motor into operation, the pin u will move the locking pawl s along with it and lift it off the cut-out switch c so that the latter is freed from the locking action 25 and is moved automatically by the action of the spring q from the non-operative position into the operative position.

r is a spring provided for the purpose of automatically returning the locking member *a* into the mid-position shown in Figure 2. This spring *r* acts upon a lever *z* which is arranged to be rotated so as to bear against the locking member *a* and to be returned by said spring into a position which is determined by a stop and which corresponds to the mid position.

In this position the contacts d and e are connected together and thereby the pilot lamp m is lighted. The lighting up of this lamp shows whether the automatic switch h (for connecting the battery l with the dynamo k immediately the latter has attained the requisite voltage) has broken

this connection immediately the voltage of the dynamo has dropped below the voltage of the battery, in order to prevent an unintentional discharge of the battery through the dynamo. 45

Having now described my invention, what I claim as new and desire to secure by Letters Patent is:—

1. A combined locking apparatus for the distributing switches of electrical installations for motor-cars, including a lighting control switch, a biased ignition switch, a movable locking member capable of resting in three positions, viz, a locking position, an unlocking mid-position and a terminal position for switching in a starting motor, a biased pivoted locking pawl, and a projection on said locking member coacting with part of said pawl, said locking pawl tending to hold said ignition switch in a non-operative position when said movable locking member rests in its mid-position and being forced aside when said ignition switch is moved over by external pressure, said locking pawl being carried along by the said projection on said movable locking member and freeing said ignition switch immediately said movable locking member is brought into its third or terminal position for starting; said ignition switch when freed being moved automatically by its own bias from the non-operative into the operative position.

2. A combined locking apparatus for the distributing switches for electrical installations for motor-cars as claimed in claim 1, including a spring tending to return the movable locking member from the terminal starting position into its mid-position. 80

In testimony whereof I have signed my name to this specification.

JACQUES BOHLL.
